No. 800,602.

PATENTED SEPT. 26, 1905.

J. S. THURMAN.
CARPET RENOVATOR.
APPLICATION FILED OCT. 23, 1902.

UNITED STATES PATENT OFFICE.

JOHN S. THURMAN, OF ST. LOUIS, MISSOURI.

CARPET-RENOVATOR.

No. 800,602.

Specification of Letters Patent.

Patented Sept. 26, 1905.

Application filed October 23, 1902. Serial No. 128,382.

To all whom it may concern:

Be it known that I, JOHN S. THURMAN, a citizen of the United States, residing at St. Louis, Missouri, have invented a certain new and useful Improvement in Carpet-Renovators, of which the following is a full, clear, and exact description, such as will enable others skilled in the art to which it appertains to make and use the same, reference being had to the accompanying drawings, forming part of this specification, in which—

Figure 1 is a side elevational view of my improved renovator. Fig. 2 is a rear elevational view of the same. Fig. 3 is a vertical longitudinal sectional view of the same. Fig. 4 is in part a vertical transverse sectional view on the line 4 4 of Fig. 3 and in part a front elevational view of the same, and Fig. 5 is a horizontal longitudinal sectional view of the same.

This invention relates to a new and useful improvement in carpet-renovators, the object being to construct a device of the character described which is capable of effectively renovating a carpet—that is, dislodging the dust and dirt therefrom when being moved in two directions—to wit, forward and backward.

Heretofore renovating-machines known as the "double" machine have been provided with a simple blast with passages for the dust-laden air on both sides thereof, and it is claimed for these machines the virtue of performing effective work when being moved forward and backward. Still other machines have been provided with a circular blast which enables the machines to be moved in any direction. In all of these machines the blast-nozzle has been fixed with relation to the casing, and it is obvious that this fixed angle of the blast is most effective when the machine is being moved in the proper direction to take advantage of the angle of the blast.

It is the prime object of my present invention to provide means in a carpet-renovator whereby when the machine is being moved in one direction the angle of the blast will be such as to most advantageously renovate the carpet and when the machine is being moved in the opposite direction the angle of the blast will be changed so as to most advantageously renovate the carpet under the changed conditions. This changing of the angle of the blast I prefer to make dependent upon the direction in which the renovator is being moved, providing means whereby it is automatically accomplished; but it is obvious that the operator

can change the angle of the blast without moving the casing over the carpet by simply manipulating the handle.

In the drawings, 1 indicates the casing, which is preferably open at its top and which discharges the dust-laden air into a dust-arresting bag 2, as has heretofore been done.

3 indicates the side walls, and 4 the bottom wall, of a dust-collecting chamber, which, with the casing 1, provides two passages for the dust-laden air on each side of the machine. The chamber in the bottom of the machine, which communicates with these passages, has the adjustable blast-nozzle located therein, as shown. At the upper ends of the passages for the dust-laden air are located the valves 5, which are lifted by the dust-laden air and direct said dust-laden air downwardly and inwardly, so as to enable the depositing of the heavier particles of dust in the chamber formed by the walls 3 and 4. To protect these valves from the accumulation of dust on their upper faces, which would tend to interfere with their proper operation, I provide shelves or extensions 6 thereover, as shown.

7 indicates the blast-nozzle, which extends transversely the machine, which blast-nozzle is provided with a removable side wall 8, secured in position by suitable screws. This removable wall is preferably finished flush on its inner face, so as to fit snugly against the body portion, and in order to provide the slit or opening through which the blast of air issues I provide thin sheets of paper or other material 9 at the side edges and at the rabbeted joint, as has heretofore been described in my former patents. The ends of the nozzle 7 have secured thereto suitable head-castings 9^a, which project through openings in the side walls of the casing. These openings, as shown in Figs. 1 and 4, are elongated, the longest diameter being less than a right angle to the axes of the operating-handle.

100

10 indicates extensions on the head-castings in the form of rock-arms, to which the yoke members 11 of the handle are pivoted. These yoke members extend forwardly from the branches of the handle, which branches are preferably made hollow to provide conduits for the compressed air, which conduits are connected by flexible pipes 12 to the chambers in the head-castings 9^a.

In operation it will be seen that when the renovator is pushed forward the handle, being connected below the pivotal point of the noz-

zle, will swing the nozzle on its pivot, the flexible pipe permitting this, and throw the nozzle forward, so that it comes in contact with the nap of the carpet, bending the same forward to enable the issuing blast of air to more readily dislodge the particles of dirt and dust in the carpet, forcing them into the forward passage and up into the chamber in the casing. The lower ends of the slots in the side walls of the casing act practically as stops; but as the lower end of the nozzle is flush with the lower face of the casing, or it may project slightly beneath the lower face of the casing, if desired, the end of the nozzle may be pressed well down into the nap of the carpet to effectually perform its work. When the direction of movement of the renovator is changed and it is pulled backward, the pressure on the handle will cause the trunnions of the blast-nozzle to ride up in their respective slots, so as to permit the angle of said nozzle to be changed. The long axis of the slot being slightly less than a right angle to the handle will cause the pull on the handle in a horizontal direction to force the end of the nozzle well down into the nap of the carpet, and the dust-laden air will now be forced up into the passage at the back of the machine.

In order that the angle of the blast-nozzle may be adjusted when the machine is being moved in either direction, I provide set-screws 13 in the bottom wall 4, which extend therethrough and coöperate with the blast-nozzle in its different positions. These set-screws may be adjusted from the interior, and when the proper angle of the nozzle has been determined for different kinds of work the machine may be operated without further adjustment.

So far as I am aware I am the first to pivotally connect a nozzle to the handle of a carpet-renovator, whereby when the renovator is in operation pressure exerted on said handle either in a direction toward the casing or from the casing to move the renovator will change the angle of the nozzle, so as to project the blast of air issuing from the nozzle in a forward direction with respect to the movement of the renovator-casing.

I am aware that many minor changes in the construction, arrangement, and combination of the several parts of my device can be made and substituted for those herein shown and described without in the least departing from the nature and principle of my invention.

Having thus described my invention, what I claim as new, and desire to secure by Letters Patent, is—

1. In a carpet-renovator, the combination with an open-bottomed casing movable over the article to be renovated, of a nozzle mounted in said casing to discharge through the opening therein, and a handle for propelling said casing and pivotally connected to said nozzle.

2. In a carpet-renovator, the combination

with a casing having elongated openings, of a nozzle trunnioned in said openings, and a handle pivotally connected to said nozzle; substantially as described.

3. In a carpet-renovator, the combination with a casing, of a nozzle movably mounted therein, and means for changing the position of said nozzle when the direction of movement of the renovator is changed; substantially as described. 70

4. In a carpet-renovator, the combination with a casing, of a nozzle movably mounted therein, a handle pivotally connected to said nozzle, and a flexible supply-pipe for furnishing compressed air to said nozzle; substantially as described. 75

5. In a carpet-renovator, the combination with a casing having two oppositely-arranged passages, one on each side, said passages converging into an enlarged chamber at the bottom of the casing, of valves at the discharge ends of said passages, and a nozzle centrally pivoted in said enlarged chamber for discharging air downward into and through the carpet being renovated, and in the direction of one or the other of said passages; substantially as described. 80

6. In a carpet-renovator, the combination with a casing having elongated openings in its side walls, a nozzle trunnioned in said openings, means for adjusting the opening in said nozzle, head-castings provided with rock-arms arranged outside the casing, and an operating-handle pivotally connected to said rock-arms; substantially as described. 95

7. In a carpet-renovator, the combination with a casing having elongated openings, of a nozzle trunnioned in said openings, means for adjusting the angular relation of said nozzle to the casing in its different positions, and a handle connected to said nozzle for changing its position; substantially as described. 100

8. In a carpet-renovator, the combination with an open-bottomed casing movable over the article to be renovated, of a swinging nozzle for discharging through the opening in said casing, means for adjustably limiting the movement of said nozzle in either direction, and means for moving said nozzle in different directions; substantially as described. 115

9. In a carpet-renovator, the combination with an open-bottomed casing, movable over the article to be renovated, of a nozzle movably mounted therein to discharge through the opening thereof, a rock-arm extension fixed to said nozzle, and a handle for propelling said renovator, and pivotally connected to said extension to reverse the direction of said nozzle. 120

10. In a carpet-renovator, the combination with a casing, of a nozzle movably mounted therein, head-castings at the ends of the nozzle, said head-castings having rock-arm extensions 10, a forked handle pivotally connected to said rock-arm extensions said handle being provided with a supply-passage for 130

compressed air, and flexible connections between said supply - passage and the hollow head-castings, which latter communicate with the nozzle-opening; substantially as described.

5 11. In a pneumatic carpet-cleaner, an open-bottomed case, an air-distributer adjustably connected with the inside faces of the ends of the case, to operate in the manner set forth for the purposes stated.

10 12. In a pneumatic carpet-cleaner, an open-bottomed case provided with an interior chamber and a passage leading from the open bottom to said chamber, and an air-nozzle adjustably connected with the inside faces of the case and in line with the mouth of the passage; substantially as described.

15 13. In a carpet-renovator, the combination with a casing, of a nozzle movably mounted therein, a rock-arm extension fixed to said nozzle, a handle provided with a blast-passage, said handle being pivotally connected with said extension, and a flexible blast-conducting pipe connected, respectively, with said nozzle and with said handle; substantially as

20 25 14. In a carpet-renovator, the combination with a casing, of a nozzle pivotally mounted therein, and a handle movable relatively to said nozzle and provided with an air-supply passage, and connections between said handle and nozzle, said connections being provided with an air-passage connecting the passage in said handle with the nozzle.

30 35 15. In a renovator, the combination with a casing, of a nozzle in said casing, means for

movably supporting said nozzle, a handle movable with reference to said casing for propelling said renovator, and connections between said nozzle and said handle to change the position of said nozzle relative to said casing to reverse the direction of discharge of air into the article to be renovated when the direction of movement of the renovator is changed.

40 16. The combination with the casing of a renovator provided with a plurality of passages through which the dust-laden air is forced, of means for supplying air to said passages, and means for shifting the supply of air from one passage to another.

45 17. The combination with the casing of a renovator provided with a plurality of passages through which the dust-laden air is forced, of means for supplying air to said passages, and a handle for propelling said renovator and shifting the supply of air from one passage to another.

50 55 18. The combination with the casing of a renovator provided with a plurality of passages through which the dust-laden air is forced, said casing being also provided with a chamber connected with said passages, of a nozzle movably mounted in said chamber.

In testimony whereof I hereunto affix my signature, in the presence of two witnesses, 60 this 21st day of October, 1902.

JOHN S. THURMAN.
